SAFETY ANTIJIMMY WINDOW LOCK

Maurice Goldwasser, Brooklyn, N. Y.

Application May 16, 1950, Serial No. 162,154

5 Claims. (Cl. 292—205)

1

This invention relates to a safety jimmyproof window lock.

It is an object of the present invention to provide a window lock whereby access to the lock cannot be had from the exterior of the window and wherein the connection of the lock with the window is effected between the two windows in such a manner that access cannot be had for the padlock and wherein there is a container for the padlock which is hinged to the inner window and which will contain the padlock in such a manner that access to the padlock can be had only from the inner side of the window.

Other objects of the present invention are to provide a safety anti-jimmy window lock which is of simple construction, inexpensive to manufacture, has a minimum number of parts, does not interfere with the operation of the window, and is compact, tamperproof and efficient in operation.

For other objects and for a better understanding of the invention, reference may be had to the following detailed description taken in connection with the accompanying drawing, in which:

Fig. 1 is a perspective view of the assembled parts of the safety lock embodying the features of the present invention and of the window parts.

Fig. 2 is a vertical sectional view taken on line 2—2 of Fig. 1.

Referring now to the figures, 10 represents an upper window having a bottom frame rail 11. To this frame rail there is attached a plate 12 from the inner edge thereof. This plate is attached by means of screws 13. The bottom end of the plate 12 is turned under the under face of the piece 11. The upper end of the vertical plate 12 extends upwardly above the upper face of the piece 11 and is provided with a hole 14 through which the hasp of a padlock 15 can be extended.

Before the padlock is put in place, a container 16 having sides and having a slot 17 is dropped over the upper end of the vertical plate 11 and is hinged to upper frame rail 18 of a lower window sash 19. The hinging of the container 16 is effected through a hinge part 21 connected to the inner face of the frame rail 18 by screws 22 and also by hinge parts 23 and 24 disposed respectively at the opposite sides of the hinge part 21 and by screws 25 and 26 respectively. The hinged end of the container 16 is open, as indicated at 27, so that the hasp of the padlock can be inserted into the opening 14 of the vertically extending plate 12. Access cannot be had to the padlock except through this opening 27. Accordingly the padlock is covered so that it cannot be tampered

2

with from the outside of the windows and so that tools working between the slit between the windows cannot contact the padlock.

When it is desired to open the window, the padlock 15 is removed from the container 16 through the open end 27 thereof after first lifting the hasp from the opening 14 in the vertically extending plate 12. The container 16 is hinged over to the position shown in dot and dash lines in Fig. 2. 10 The windows can be moved up and down as freely as with windows without the locking arrangement. In order to insert and lock the hasp of the padlock it is necessary to put the padlock in an inclined position within the container in order 15 to have sufficient support on the upper end of the plate 12 for pushing the hasp into the padlock.

While various changes may be made in the detail construction, it shall be understood that such changes shall be within the spirit and scope of the 20 present invention as defined by the appended claims.

Having thus set forth and disclosed the nature of my invention, what is claimed is:

1. In a safety anti-jimmy window lock having a vertical plate adapted for connection to the lower rail of an upper window sash and adapted to project above the same, said vertical plate having a hole in its upper end and adapted to receive a hasp of a padlock, a container having sides and an opening in the bottom thereof adapted to receive the upper end of the vertical plate and the said padlock disposed within the container.

2. In a safety anti-jimmy window lock having a vertical plate adapted for connection to the lower rail of an upper window sash and adapted to project above the same, said vertical plate having a hole in its upper end and adapted to receive a hasp of a padlock, a container having sides and an opening in the bottom thereof adapted to receive the upper end of the vertical plate and the said padlock disposed within the container, said container being open at its inner end for access to the padlock lying within from the 45 inside of the window.

3. In a safety anti-jimmy window lock having a vertical plate adapted for connection to the lower rail of an upper window sash and adapted to project above the same, said vertical plate having a hole in its upper end and adapted to receive a hasp of a padlock, a container having sides and an opening in the bottom thereof adapted to receive the upper end of the vertical plate and the said padlock disposed within the container, said container being open at its inner end 55

and means for hingedly connecting the inner end of the container to the upper edge of a lower window sash.

4. The safety anti-jimmy window lock as defined in claim 3, and said hinge means comprising hinge plates adapted for connection to the front edge of the upper rail of the lower window sash and for connection to the top face of the upper rail of the lower window sash.

5. In a safety anti-jimmy window lock having a vertical plate adapted for connection to the lower rail of an upper window sash and adapted to project above the same, said vertical plate having a hole in its upper end and adapted to receive a hasp of a padlock, a container having sides and an opening in the bottom thereof adapted to receive the upper end of the vertical plate and the said padlock disposed within the con-

tainer, said vertical plate having an outwardly turned flange adapted to engage with the under face of the lower rail of an upper window sash.

MAURICE GOLDWASSER.
